[57] **CLAIM**

The ornamental design for an in-line skate, as shown and described.

DESCRIPTION

FIG. 1 is a front, top and right side perspective view of an in-line skate embodying my new design;

FIG. 2 is a left side elevational view thereof;

FIG. 3 is a top plan view thereof;

FIG. 4 is a bottom plan view thereof;

FIG. 5 is a front elevational view thereof; and,

FIG. 6 is a rear elevational view thereof.

The broken line showing of the wheels in FIGS. 1, 2 and 4-6 is for illustrative purposes only and forms no part of the claimed design.
